UNITED STATES PATENT OFFICE.

ELIZABETH HOYT IVES, OF MEADVILLE, PENNSYLVANIA.

INSTRUCTIVE GAME.

SPECIFICATION forming part of Letters Patent No. 739,678, dated September 22, 1903.

Application filed March 9, 1903. Serial No. 146,924. (No model.)

To all whom it may concern:

Be it known that I, ELIZABETH HOYT IVES, of the city of Meadville, county of Crawford, and State of Pennsylvania, have invented 5 certain new and useful Improvements in Instructive Games, of which the following is a full, clear, and exact specification, reference being had to the accompanying drawings, wherein—

10 Figures 1, 2, 3, and 4 are illustrations of objects representing words or phrases which are parts of titles of literary works. Figs. 5, 6, and 7 are portraits of authors; and Figs. 8 and 9 are pictures similar to those shown in 15 Figs. 1, 2, 3, and 4, but set together so as to compose a complete title of a literary work.

My invention relates to utensils for playing instructive games; and it consists in devising and arranging cards bearing pictorial representations of words or phrases composing titles of literary works, combining them into series and in combining therewith portraits of the authors of works, the titles whereof are represented, and finally in the arrangement of games to be played by means of such cards.

The figures of the drawings are front views of cards made according to my invention.

Fig. 1 of the drawings shows a card bearing the conventional representation of a tramp. Fig. 2 illustrates a heap of stones. Fig. 3 shows an ax with the letter Centwined with the handle of the ax. Fig. 4 shows the letter A expanded laterally. Fig. 5 is the 35 portrait of Bulwer-Lytton; Fig. 6, that of Mark Twain; Fig. 7, that of Stevenson; and Figs. 8 and 9 show two cards joined together, showing, respectively, one a bee with the letter E and the other a pair of human hands 40 tied together by a rope.

By joining together Figs. 1 and 4 in their successive order, the pictorial representation of the words "A tramp abroad" is obtained, which is the title of Mark Twain's popular 45 book. The same, by joining Figs. 3 and 2, the pictorial representation of the word "Cax-stones" (Caxtons) is obtained, which is the title of Bulwer-Lytton's work. Figs. 8 and 9 joined together, as shown in the drawings, 50 represent the title of Stevenson's novel "Ebb-Tide." The cards are of course also capable of being combined differently and are in this respect like the letters of an alphabet, except that they are devised with the object in view to represent only such syllables, words, or phrases of which the titles of meritorious literary works are composed. 55

The cards can be used without the portraits of the authors. The cards bearing the portraits of the authors have the object to indicate to some extent what literary works are represented by the cards of a set. They also serve in the game of solving problems to compose from the cards one or more titles of works written by a designated author or of 65 the problem to select from them the author who has written a given work. The cards with the portraits of authors serve also in the game, as I shall explain farther on, to make up the sets of works by exchanging the cards 70 among the players.

The number of the cards and the number of the sets are limited.

The cards may be provided with letters or numbers—as, for instance, shown on Figs. 1, 4, and 6. Figs. 1 and 4 (designated by the same letter G) represent words or phrases forming parts of the title of a work of one author; the same letter is indicated on the card bearing the portrait of the author. Such 80 designating of the cards of one group facilitates the separating of the cards into sets for individual instruction and of course simplifies the problem of composing the titles of the works written by the particular author. 85 The cards may also be provided with the consecutive numbers or indications (see Figs. 1 and 4) indicating the manner of combining them into titles of works. When in such arrangement, the sets are in the nature of rebuses, the solution of which is the rudimental application of the products of my invention. After the pupils have acquired the knowledge of the titles of the works represented in the cards they may be required to compose from 90 the cards the titles of the works of a given author or to select from the cards bearing the portrait of authors the author of the work represented by a set of title-cards given to the pupil. Then again a game can be played 95 by dealing out indiscriminately to each participant an equal number of cards and requiring them to complete the titles or sets of titles from the remaining stock of cards. Many other systems of instructive games may be practiced by means of the cards, all of 5 which, however, require instruction in literature and all of which are tending to improve the knowledge of the participant of the works of various authors and stimulate the study of literature and reading of meritorious books.

10. I claim as my invention—

1. A game device consisting of cards bearing rebuses representing syllables, words or phrases, forming component parts of titles of literary works.

15. 2. A game device consisting of cards bearing rebuses representing syllables, words or phrases forming component parts of titles of literary works, and cards bearing portraits of authors of the works, the titles whereof are represented in the other cards. 20

3. A game device consisting of sets of cards, each set comprising cards bearing rebuses representing component syllables, words or phrases of the title of a literary work. 25

4. A game device consisting of sets of cards, each set comprising cards bearing rebuses representing component syllables, words or phrases of the title of a literary work, and a card bearing the portrait of the 30 author of the works, the titles whereof are represented in the other cards of the set.
